(57) CLAIM

The ornamental design for a chair, as shown and described.

DESCRIPTION

FIG. 1 is a perspective view of a first embodiment of a chair, showing our new design;

FIG. 2 is a top plan view thereof;

FIG. 3 is a bottom plan view thereof;

FIG. 4 a front elevation view thereof;

FIG. 5 is a back elevation view thereof;

FIG. 6 is a side elevation view thereof, with the opposite side elevation view being a mirror image thereof;

FIG. 7 is a perspective view of a second embodiment of a chair, showing our new design;

FIG. 8 is a top plan view thereof;

FIG. 9 is a bottom plan view thereof;

FIG. 10 a front elevation view thereof;

FIG. 11 is a back elevation view thereof; and,

FIG. 12 is a side elevation view thereof, with the opposite side elevation view being a mirror image thereof.

The dash-dot broken lines illustrate a boundary of the claimed design and form no part thereof.

1 Claim, 12 Drawing Sheets
